LENS-GRINDING MACHINE.

1,184,831.

Specification of Letters Patent. Patented May 30, 1916.

Application filed May 2, 1911. Serial No. 624,600.

To all whom it may concern:

Be it known that we, GEORGE H. DAY and LUCIAN W. BUGBEE, citizens of the United States, residing at Southbridge, in the county of Worcester and State of Massachusetts, have invented certain new and useful Improvements in Lens-Grinding Machines, of which the following is a specification.

Our invention relates to improvements in lens grinding machines and is particularly intended for use in connection with grinding toric and cylindrical lenses. Our invention as applied to grinding lenses of toric and cylindrical forms comprises a lower grinding tool or form, an upper grinding tool, means for simultaneously reciprocating the upper tool across the lower tool in two directions transverse to each other, the resultant of which will cause a given point on the upper tool to travel in a curvilinear path across the face of the lower tool; arbitrary means for varying the amplitude of the reciprocations in one direction; means adapted to progressively and automatically vary the path of the reciprocations relative to the center line of the lower grinding tool transverse to the first reciprocations; arbitrary means for adjusting the limits within which the automatic varying means operate; arbitrary means for regulating the transverse initial position of the upper grinding tool; means for throwing the upper tool out of contact with the lower tool; means for securing the lower tool in position; means for securing the upper tool to the transverse reciprocating member in such a way that the upper tool will be lifted out of contact with the lower tool when the transverse member is lifted; means for causing the upper tool to engage the lower tool under pressure; means for securing the lenses to the grinding tools, and means for maintaining parallelism between the axis of the lens and the corresponding axis of the grinding tools.

The principal object of our invention is to provide means whereby the reciprocations of the grinding tool in the two directions may be varied independently of each other and the curvilinear path of the upper tool over the lower tool arbitrarily adjusted and determined upon.

Another object of our invention is to provide a feed which will automatically and progressively vary the path of the reciprocations in one direction relative to the center line of the lower grinding tool.

Another object of our invention is to provide arbitrary means for regulating the automatic feed.

Other objects of our invention are to provide means for positioning the upper tool on the lower tool; for holding the upper tool on the lower tool under pressure in such a way as to maintain the parallelism of the lens and grinding tools; for lifting the upper tool off the lower tool when the transverse reciprocating arm is lifted; for readily changing the lower tool; for throwing the upper tool out of contact with the lower tool when the parts are operating, and for housing the operating parts.

With these and other objects in view, the invention consists in the novel construction and arrangement of parts hereinafter described, delineated in the drawings and specifically claimed, it being understood that changes properly falling within the scope of what is claimed may be made without departing from the spirit of the invention.

Similar numerals of reference are employed to denote corresponding parts throughout the several figures of the drawings.

In the accompanying drawings: Figure I is a top or plan view of the machine with the top casing removed. Fig. II shows an end view of the machine with a part of its casing broken to show internal arrangements. Fig. III is a transverse section through the lower tool showing the securing arrangements. Fig. IV is a longitudinal section through Fig. III. Fig. V shows a sectional detail view of the automatic feed arrangement taken on line V—V, Fig. I, shown to opposite hand. Fig. VI is a plan or top view of Fig. V. Fig. VII is a section or side view of the upper tool holding arrangements. Fig. VIII is a detail elevation or side view of the upper tool holding arrangements. Fig. IX is an end view or elevation of Fig. VIII, certain portions being omitted. Fig. X is a diagram of the curvilinear path of a given point in the upper tool as it moves over the lower tool show-

ing the progressive variation of the path of the transverse reciprocations by means of the automatic feed.

For convenience of description, motions or reciprocations in a line parallel with the driving shaft of the machine will be referred to as longitudinal, whereas those at right angles to this direction will be referred to as transverse movements or reciprocations.

10 The mechanism of the machine is suitably mounted on a bed plate or frame 1, and a housing or cover 2 is provided to protect as much of the mechanism as practicable from the abrasive or grinding mixture which is employed between the lens holding or grinding tools. The lower grinding tool 3 which is stationary is held on a boss 4 on the frame 1 by means of dowel pins 5 and an interlocking cam 6 fitting into a 20 groove or recess 7 in the under side of the tool 3. This interlocking cam may be thrown in or out of position by means of a lever 8, or other suitable mechanism as preferred. The upper tool 9 is operatively connected with the main power or driving shaft 10 in such a way that it will be reciprocated in both a longitudinal and a transverse direction, the resulting path of which will be curvilinear as indicated in 30 Fig. X.

The longitudinal reciprocating means will now be described: The power is supplied through a shaft 10 which is thrown in and out of engagement in the usual manner by the fast and loose pulleys 24 and 25. A vertically disposed screw gear 11 which is slidably keyed to the power shaft 10 meshes with a horizontally disposed screw gear 12 which is suitably mounted in a sleeve 40 13 attached to the bed plate or frame 1. In the upper face of the horizontal screw gear 12 is a slot-way 14 in which slides a shoe 15, to which is pivotally connected a link 16 which is in turn pivoted at 17 to 45 a rocking lever 18 which is pivoted at one end to the frame at 19 and at the other end to a block 20 secured to and turning with the main power shaft 10 which is slidably mounted in its journals. The shoe 15 is 50 adjusted in the slot 14 in the horizontal gear by means of a set bolt 21 or similar locking device, while the end of the rocking lever 18 which engages the block 20 is bifurcated or formed into a yoke having embracing 55 arms which are provided with pins 22 slidably fitting into a groove 23 in the block 20.

The mechanism transversely reciprocating the upper grinding tool will next be described: This mechanism consists of two parts, one to transmit the direct reciprocations, and a feed gear designed to progressively and automatically change the path of the direct reciprocations. The direct reciprocations are transmitted through an ec-

centric arm 26 which is pivoted on the driving shaft 10 by means of two eccentrics 27, the eccentrics being connected with the main body of the arm 26 by the bifurcated members 28, while the outer end of the arm 26 is fashioned into a handle 29 by which the arm may be lifted, pivoting about the shaft 10. The eccentrics 27 are fixedly secured to the shaft 10 and the shaft end of the arm 26 is divided to form a bearing 75 around the eccentrics 27, said divided members 30 and 31 being held together in the usual manner by bolts. The eccentrics 27 revolve with the shaft 10 and give a transverse reciprocating motion to the eccentric 80 arm 26. The upper tool 9 is operatively attached to the eccentric arm 26 through the connecting strap 32 which is pivoted to the arm 26 at 33 and carries at its lower end a pin 34, the under end 35 of which is 85 pointed to universally engage a socket 36 in the upper tool 9.

The upper tool 9 is maintained in parallel alignment with the lower tool 3 by means of spring forks 37 secured to the cross bar 38 which is pivoted on the pin 39 extending into the block 40 which in turn is pivoted by the pins 41 to the rocking bracket 42 which is in turn pivoted at 43 to the eccentric arm 26. The spring 44 which is 95 attached at 45 to the eccentric arm 26 and at 46 to the pivot pin 39 draws the spring forks toward the eccentric arm 26 and consequently maintains the upper tool 9 in contact with the pin 34 in the arm 32. Pivot 100 bearing points 47 are provided on the spring fork 37 to fit into corresponding recesses in the upper tool 9 so that the tool 9 during the reciprocations of the arm 26 will adjust itself to the curvature of the lower tool 105 in one direction by means of the pivotal movement on the points 47 and in a direction transverse thereto by means of a corresponding pivotal movement of the cross bar 38 on the pin 39 secured to the block 40. 110

The upper tool 9 is progressively fed transversely across the lower tool 3 by means of the connecting rod 48, which causes the connecting strap 32 to oscillate about its fulcrum 33. The rod 48 is journaled on a slide 115 bolt 49 fitting in a groove 50 in the head of a pivot bolt 51 which extends through a friction bearing 52 integrally formed on the divided arm 23 of the eccentric arm 26. On the pivot bolt 51 is mounted a ratchet wheel 120 53 in such a way that its teeth engage pawls 54 which are pivotally attached to an oscillating arm 55 which is also pivoted on the pivot bolt 51 and extends therefrom toward, and has its opposite end divided to 125 slidably embrace the shaft 10 about as shown in Fig. V. The end of the oscillating arm 55 which embraces the shaft 10 will remain in relative position to that shaft as it turns, whereas the end which is pivoted to the 130

5 pivot bolt 51 will travel in a reciprocating path whose course is transmitted by the eccentric 27 through the eccentric arm 26 to which the friction bearing 52 is integrally secured. This differential movement of the two ends of the oscillating arm 55 will cause an oscillation of the end to which the pawls are pivoted through an angle having its apex at the center of the pivot bolt 51. This 10 oscillation will cause the teeth of the pawls 54 to engage the teeth of the ratchet 53 and advance it accordingly. This movement which has been transmitted to the ratchet wheel 53 will in turn be transmitted to the 15 pivot bolt 51 in the head of which the slide bolt 49 is adjustably secured in the groove 50. If the bolt 49 is adjusted so that its axis coincides with the axis of the pivot bolt 51, there will be no linear motion transmitted to the 20 connecting rod 48, but if the bolt 49 is adjusted to one side or the other of the axis of the pivot bolt 51 an eccentric movement will be set up and the corresponding linear motion transmitted to the connecting 25 rod 48. The number of teeth in the ratchet wheel 53 may be selected as desired and by the use of two pawls this wheel may be advanced one half the circular pitch of one tooth to each revolution of the shaft 10; as 30 for example—if there were fifty teeth in the ratchet wheel 53 it would require one hundred revolutions of the driving shaft 10 to make one complete revolution of the pivot bolt 51.

35 In the diagram shown in Fig. X the curve shown as a solid line represents the curvilinear path of a point of the upper tool 9 across the lower tool when there is no feed motion to vary the path of transverse reciprocation; *i. e.*, when the axis of the bolt 49 coincides with the axis of the pivot bolt 51. The curve shown in dotted lines represents the progressive advance of the path of the 40 transverse reciprocations away from the longitudinal center line of the lower grinding tool when the automatic feed gear is operating. In the diagram it will be understood that the several transverse reciprocations are shown as occurring during the 45 period of a single longitudinal reciprocation, and also that the number of such reciprocations is for purpose of illustration only and not necessarily correct. The progressive advancement of the path of the transverse reciprocations will be within its limits between the parallel lines "BB"—BB; variation between these limits being attained by one 50 complete revolution of the pivot bolt 51. The amplitude or the distance between the lines A—A and B—B may be varied by adjusting the slide bolt 49 in the slot 50 in the head of the pivot bolt 51, the amount of eccentricity of this adjustment determining the distance between A—A and B—B.

55 If it is found that one section or portion

of the grinding tools is worn more than the others, the position of the upper tool with respect to the lower may be varied in a transverse direction by means of a shortening or lengthening device in the connecting arm 48. In the arrangement shown in Figs. I and II this device is formed by making the connecting rod 48 in two parts and uniting them by a bolt 57 which has a right and left hand thread connection with the respective parts. Fixedly attached to the bolt 57 is a head 58 which may be turned with a wrench or other tool so as to shorten or lengthen the distance between the parts of the connecting rod 48. As the connecting rod 48 is pivoted to the connecting strap 32 at 56 this shortening or lengthening operation will oscillate the connecting strap 32 about its pivot 33 and change the position of the upper tool 9 on the lower tool 3 as 85 desired.

90 The upper tool 9 may be lifted or thrown out of contact with the lower tool 3 either when the machine is idle or when operating, by means of an offset crank 59 suitably mounted in its journals 60 on the frame of the machine. This offset arm is located under the eccentric arm 26 and is thrown into engagement with that member by means of a crank handle 61 suitably located out of the way of the working parts. The offset crank is kept either in engaged position with the eccentric arm 26 or in its normal non-engaged position by means of a spring 62 which has one end attached at 63 to the cranked arm 100 61 and the other end securely held on the frame of the machine.

95 The upper tool 9 is made to engage the lower tool 3 under pressure by means of a spring 64 which has one end held at 65 on the eccentric arm 26 and the other end attached to an eye 66 on the bed plate.

100 The lens to be ground is ordinarily held in place by being cemented to the upper tool 9 but it may be similarly attached to the 110 tool 3 if so desired.

105 The operation is as follows: The motive power is applied through the shaft 10 by means of the pulleys 24 and 25 in the usual manner. The shaft 10 is given a longitudinal reciprocation by means of the screw gears 11 and 12 which operating through the eccentric link motion of the parts 16 and 18 cause the block 20, which is fixedly attached to the shaft, to carry the shaft back and forth in its bearings. The eccentric arm 26 which carries the upper tool is given a longitudinal reciprocation through the link motion just described and a transverse reciprocation through its eccentric connections 115 27 to the shaft 10. The path of the transverse reciprocations may be automatically varied through the connecting rod 48 operating through its eccentric adjustment with the bolt 49 in the pivot bolt 51 which is pro- 120 125 130

gressively advanced by means of the oscillating arm 55 operating the pawls 54 and the ratchet wheel 53, as previously described. The amount of the variation of this path 5 depends on the eccentric adjustment of the bolt 49 in the slot 50 on the pivot bolt 51. The initial or starting position of the upper tool on the lower tool may also be arbitrarily varied in a transverse direction by means of 10 the adjusting bolt 57 which operates the connecting strap 32, engaging the tool holder. The upper tool is so secured to the eccentric arm 26 that it is always held against the pivot point 35 of the pin 34 and will travel 15 with the arm 26 when the same is lifted about its pivot on the shaft 10. The upper tool is also held in parallel alignment with the lower tool by means of the spring forks 37 and may adapt itself to the contour of 20 the lower tool through the oscillating connections of the said forks, as previously described.

To place a lens in position to be ground the eccentric arm 26 is lifted pivoting around 25 the shaft 10. This arm may be lifted either by the handle 29 or by the handle 61, as desired, the only difference being that if handle 61 is used the arm 26 will rest on the offset crank 59 and remain in its raised position. The lens 67 is cemented to the upper 30 tool 9 which is placed between the spring forks 37, as previously described. The abrasive mixture is then applied between the lens and the lower tool and the arm 26 lowered, 35 the pointed end of the pin 35 engaging the recess 36 in top of the tool 9 and holding it in place on the lower tool through the pressure of the spring 64. The power is then applied and the lens 67 is reciprocated 40 across the lower tool by means of the mechanism previously described, the lens remaining in parallel alignment with the lower tool during this operation.

It will be noted that the lens may be lifted 45 with the upper tool 9 off of the lower tool whenever desired by raising the arm 26, which will facilitate the supplying of the abrasive material as it becomes exhausted, and permit the progress of the grinding to 50 be examined at will.

It will also be noted that the lens and upper tool may be thrown out of contact with the lower tool while the machine is in motion or operating, by throwing up the offset crank 59 by means of the handle 61, thus permitting the work to be examined or the abrasive material to be supplied without stopping the movement of the machine, which is considered quite an advantage in 60 a mechanism of this kind.

It will also be noted that the amplitude of the longitudinal reciprocations may be adjusted independently of the transverse reciprocations, being arbitrarily adjusted, and

the transverse reciprocations being both arbitrarily and automatically adjustable. 65

It will also be seen that by properly selecting the number of teeth in the feed ratchet wheel 53 and by making a proper gear ratio in the screw gears 11 and 12, 70 which should not be multiples of each other, the path of the upper tool over the lower tool will be broken up and it will be at very rare intervals that a given point in the upper tool will repeat its path over the lower 75 tool, which is a very desirable feature in the grinding of lenses, as it prevents grooves from being worn into their surfaces, and insures a smooth and even polish as well as distributing the wear uniformly over the 80 lower tool.

The arrangements shown in Figs. III and IV permit the ready change of the lower tools of various curvatures and facilitate the work in allowing changes to be made from 85 one form to another, it only being necessary to throw out the cam gear by means of a suitable handle to release the tool from its seat.

We have explained the principle of our 90 machine and the preferred form for carrying it into operation but it is apparent that many changes in details may be made without departing from the spirit of our invention and we, therefore, do not wish to be 95 limited to the arrangements shown and described.

Having described our invention, what we claim as new therein and desire to secure by Letters Patent is:

1. In a machine of the character described, the combination with members to 100 grind a lens held between them, of means for shifting one of said members in a serpentine path relative to the other, the said shifting means including a variable length arm and suitable arm shifting mechanism, an eccentric coupled with the variable length arm, and means for varying the position of the eccentric and thus the length 105 of the arm, whereby the limits of the serpentine path are varied proportional to the variance in length of the arm, substantially as described.

2. In a machine of the character described, the combination with a grinding member and a lens holder, of a variable length arm engaging one of said members, means for reciprocating the arm and member engaged thereby as a whole, and a 110 driven eccentric coupled with the variable length arm and serving to expand or contract the length of the arm to vary the path covered by the member engaged by the arm during reciprocations of the same amplitude. 115

3. The combination with grinding members adapted to grind a lens held between them, of a rotatably endwise slidable shaft

operatively connected with one of the grinding members, a block on the shaft, intermeshing gears one of which is mounted on the shaft, and an eccentric link gear uniting 5 the gear remote from the shaft with the block so as to slidably operate the shaft in its journals.

4. The combination with grinding members adapted to grind a lens held between them, of a shaft operatively connected with one of the grinding members, a block on 10 said shaft, intermeshing gears, one of which is mounted on the shaft, and an eccentric link gear uniting the gear remote from the shaft with the block so as to slidably operate the shaft in its journals, and means for 15 arbitrarily fixing the limits within which the shaft is slidably operative.

5. In a lens grinding machine, the combination 20 with a power transmission arm and means for actuating the arm, of a supplemental section carried by the arm and terminating in a contact point for engaging a block or lap, a rotatably mounted eccentric, 25 means for rotating the eccentric, and a connection between the eccentric and the supplemental member, whereby actuation of the eccentric through the connection shifts the supplemental section to vary the relation 30 of its point to the arm, substantially as and for the purpose described.

6. The combination with grinding members adapted to grind a lens held between them, of a shaft, an eccentric transverse reciprocating arm operatively engaging the 35 shaft, a rocker arm pivoted on the reciprocating arm and operatively engaging one of the grinding members, and means on the transverse reciprocating arm for operating 40 the rocker arm so as to automatically vary the path of the transverse reciprocations transmitted by the reciprocating arm.

7. The combination with grinding members adapted to grind a lens held between them, of a shaft connected with one of the 45 grinding members by a transverse reciprocating member, means for automatically varying the path of the transverse reciprocations comprising an oscillating arm pivoted on the transverse reciprocating member and non-rotatably engaging the shaft, pawls on the oscillating arm, a ratchet wheel journaled on the transverse reciprocating member and adapted to engage the pawls, 50 a connecting rod operatively engaging one of the grinding members, and means for transmitting motion from the ratchet wheel to the connecting rod.

8. The combination with grinding members adapted to grind a lens held between them, of a shaft connected with one of the 60 grinding members by a transverse reciprocating member, means for automatically varying the path of the transverse recipro-

cations comprising an oscillating arm pivoted on the transverse reciprocating member and non-rotatably engaging the shaft, pawls on the oscillating arm, a ratchet wheel journaled on the transverse reciprocating member and adapted to engage the pawls, a 65 connecting rod operatively engaging one of the grinding members, means for transmitting motion from the ratchet wheel to the connecting rod, and arbitrary means for fixing the limits within which the means for 70 automatically varying the path of the transverse reciprocations operate.

9. The combination with grinding members adapted to grind a lens held between them, of a shaft connected with one of the 80 grinding members by a transverse reciprocating member and means for automatically varying the path of the transverse reciprocations comprising an oscillating arm pivoted on the transverse reciprocating 85 member and non-rotatably held against the shaft, a connecting rod operatively engaging one of the grinding members, and an intermittently operating feed gear operatively connecting the oscillating arm and 90 the connecting rod.

10. The combination with grinding members adapted to grind a lens held between them, of a shaft connected with one of the 95 grinding members by a transverse reciprocating member, a rocker arm pivoted on the reciprocating member and operatively engaging one of the grinding members, an eccentric coupled with the rocker arm, and means for actuating the eccentric for oscillating the rocker arm and fixing the initial 100 position of the grinding member engaging the rocking arm with respect to the other grinding member.

11. In a machine of the character described, the combination with members adapted to grind a lens held between them, of mechanism for imparting a relative movement compounded of longitudinal and transverse reciprocations to the said members, 105 said means including an extensible sectional arm having engagement with one of the members, an intermittently operating rotatably mounted eccentric, means for rotating the eccentric, and a pitman extending from 110 the eccentric to one of the arm sections, whereby actuating of the eccentric serves through the pitman to vary the position of the arm section, substantially as and for the purpose described.

12. The combination with grinding members adapted to grind a lens held between them, of a shaft operatively connected with one of the grinding members by a transverse reciprocating member, a rocking arm pivoted on the reciprocating member and operatively engaging the grinding member, a 125 divided connecting arm having one end piv-

oted to the reciprocating member and the other to the rocker arm, and adjustable means uniting the divided parts of the connecting arm whereby the distance between them may be varied and the rocker arm positioned.

13. The combination with grinding members adapted to grind a lens held between them, of a shaft operatively connected with one of the grinding members by a transverse reciprocating member, a rocker arm pivoted thereon and having a pointed portion pivotally seated in a recess of the grinding member, a spring fork pivotally attached both to the reciprocating arm and to the grinding member and yielding means adapted to draw the spring fork toward the reciprocating arm and preserve the contact of the pointed portion of the rocker arm in the socket of the grinding member.

14. The combination with grinding members adapted to grind a lens held between them, of a reciprocating member operatively connected with one of the grinding members and means for adapting the reciprocating grinding member to the curvature of the other grinding member and holding it in parallel alinement therewith, comprising a rocker arm pivoted to the reciprocating member, a block pivoted to the rocker arm and a spring fork pivoted to the block at one end and pivotally embracing the grinding member at the other substantially as shown and described.

15. The combination of a grinding member having a socket, a pedestal, a dog pivoted on the pedestal and means for throwing the dog in and out of engagement with the socket in the grinding member.

16. The combination of a grinding member having a locking socket, a pedestal, means for positioning the grinding member on the pedestal, a locking dog and means for throwing the dog in and out of the locking socket.

17. The combination of a grinding member having a locking socket, a pedestal, a locking dog on the pedestal and means for throwing the dog in and out of the socket.

18. The combination of a pivoted reciprocating arm, a cam and a crank adapted to throw the cam into engagement with the reciprocating arm and move it about its pivot.

19. The combination of a pivoted reciprocating arm, a lift bar transversely disposed to the arm and means for operating the lift bar whereby it will move the reciprocating arm about its pivot without interrupting its reciprocations.

20. The combination of a pivoted reciprocating arm, lifting means, means for operating the lifting means whereby it will move the reciprocating arm about its pivot without interrupting its reciprocations.

21. The combination of a pivoted reciprocating arm, lifting means, means for operating the lifting means whereby it will move the reciprocating arm about its pivot without interrupting its reciprocations, and means to retain the lifting means in raised and lowered positions.

22. The combination of a pivoted reciprocating arm, a lift bar transversely disposed to the arm, a bearing on the lift bar adapted to slidably engage the reciprocating arm and means for throwing the lift bar into engagement with the reciprocating arm so as to move it about its pivot without interrupting its reciprocations.

23. The combination with grinding members adapted to grind a lens held between them, of a pivoted reciprocating arm, a grinding member operatively engaging the reciprocating arm, means adapted to hold the grinding tool on the reciprocating arm as it is moved on its pivot, and yielding means for holding the grinding members together under pressure.

24. The combination of a main shaft slidably mounted in journals on the frame, a gear on the shaft, a gear journaled on the frame and meshing with the gear on the shaft, a block on the shaft and turning therewith, a fork lever pivoted to the frame and having bifurcated members engaging an annular groove in the block on the shaft, a slot in the face of the gear mounted on the frame, an adjustable shoe in the slot, a link pivoted to the shoe at one end and to the bifurcated lever at the other and means for locking the shoe in position in the slot so as to regulate the eccentric movement of the bifurcated lever and the consequent reciprocation of the driving shaft in its journals.

25. The combination with grinding members adapted to grind a lens held between them, of a main shaft, eccentrics on the main shaft, a transverse reciprocating arm operatively engaging the eccentrics, a rocker arm pivoted on the reciprocating arm and having a pointed member pivotally engaging a socket in one of the grinding members, a connecting rod substantially parallel with the reciprocating arm and having one end pivoted to a bearing on the said arm and the other end pivotally engaging the rocker arm, an oscillating arm having one end held on the main shaft and the other end pivoted to an integral bearing on the reciprocating arm, pawls on the oscillating arm, a ratchet wheel journaled in the integral bearing on the reciprocating arm and engaging the pawls, a pivot pin in the bearing on the reciprocating arm uniting the ratchet wheel and the end of the connecting rod, and means on the pivot pin for eccentrically adjusting the end of the connecting rod and

regulating the throw of the rocker arm pivoted at the other end of the reciprocating arm.

26. The combination with grinding members adapted to grind a lens held between them, of a main shaft, eccentrics on the main shaft, a transverse reciprocating arm operatively engaging the eccentrics, a rocker arm pivoted on the reciprocating arm and having a pointed member pivotally engaging a socket in one of the grinding members, a connecting rod substantially parallel with the reciprocating arm and having one end pivoted to a bearing on the said arm and the other end pivotally engaging the rocker arm, an oscillating arm having one end held on the main shaft and the other end pivoted to an integral bearing on the reciprocating arm, pawls on the oscillating arm, a ratchet wheel journaled in the integral bearing on the reciprocating arm and engaging the pawls and a pivot pin in the bearing on the reciprocating arm uniting the ratchet wheel and the end of the connecting rod.

27. The combination of a reciprocating arm, a rocker arm pivoted on the reciprocating arm, a pin bearing on the rocker arm, a grinding member having a recess adapted to engage the pin bearing, a second rocker arm pivoted to the reciprocating arm, a block pivoted to the second rocker arm, and a spring fork pivotally engaging the grinding member at one end and the block at the other and a spring connecting the spring fork and the reciprocating arm so as to hold the grinding member against the pin on the rocker arm.

28. The combination with grinding members adapted to grind a lens held between them, of a shaft operatively connected with one of the grinding members by a transverse reciprocating member, means on the reciprocating member for reciprocating the grinding member in unison with and variably with respect to the reciprocations of the transverse reciprocating member and means for resiliently holding the grinding member in engagement with the various reciprocating means when the grinding members are separated.

29. The combination with grinding members adapted to grind a lens held between them, of a rotatable endwise slidable shaft operatively connected with one of the grinding members, a shift collar on the shaft, intermeshing gears one of which is mounted on the shaft and the other on a suitable support, a support having a projection adjacent the latter gear, a shift yoke having one end fulcrumed to the support and the other engaging the shift collar on the shaft, and a link eccentrically pivoted to the gear on the support and having its other end pivoted to the shift yoke, whereby as the gear is ro-

tated the link operates the yoke to longitudinally shift the shaft.

30. The combination with a support, of a fork pivotally supported thereby for universal movement with respect thereto, a tool carried by the fork, an arm pivoted to the support and engaging the tool, means for reciprocating the support and parts carried thereby, and means operated by the reciprocating means for rocking the pivoted arm to shift the tool relative to the support.

31. The combination with a support, of a fork pivotally supported thereby for universal movement relative thereto, a tool carried by the fork, an arm pivoted to the support and engaging the tool, means for resiliently holding the tool in engagement with the arm, means for reciprocating the support and parts carried thereby, and means operated by the reciprocating means for rocking the pivoted arm to shift the tool relative to the support.

32. The combination with a support, of a fork pivotally supported thereby for universal movement relative thereto, a tool carried by the fork, an arm pivoted to the support and engaging the tool, means for reciprocating the support and parts carried thereby, means for longitudinally moving the entire device to serve in conjunction with the reciprocating means to impart a sinuous movement to the tool, and means operated by the reciprocating means for rocking the pivoted arm to shift the tool relative to the support to cause the tool to have a diagonally directed sinuous movement.

33. The combination with a rotatable shaft, of an eccentric secured on the shaft for rotation therewith, a support having an eccentric strap engaging the eccentric, a tool arm pivoted to the support, and means pivoted to the support and connecting the tool arm with the shaft to rock the arm relative to the support as the support is reciprocated through the action of the eccentric upon rotation of the shaft.

34. In a grinding machine, the combination with a lens holding member and a lens grinding member, of a power shaft, and three eccentrics having driving connection therewith, connections between one of the first mentioned members and one of the eccentrics for imparting a transverse reciprocation to the member, connections between one of the members and a second of the eccentrics for imparting a longitudinal reciprocation to said member, and connections between the third of the eccentrics and one of the members for imparting a supplemental reciprocation to the member independent of the action of the other eccentrics.

35. In a grinding machine, the combination with a lens holding and a lens grinding member, of a driven shaft, rotatable eccen-

trically located driving members in operative connection with said shaft, connections between two of said devices and one of the lens holding or grinding members for longitudinally reciprocating said member at one rate, and for transversely reciprocating it at a different rate, whereby said member is relatively shifted in a varying curve path lying within a predetermined zone, and connections between another of said eccentrically disposed members and the holding or grinding member for supplementally reciprocating it at a different rate and relative to one of the other reciprocating movements imparted to it, whereby said last mentioned reciprocations progressively vary the limits of the zone in which the member is operated.

36. In a grinding machine, the combination with a lens holding member and a lens grinding member, of a plurality of driven

eccentrics, connections between one of the eccentrics and one of the members for longitudinally reciprocating said member at a fixed rate, connections between another of the eccentrics and one of the members for transversely reciprocating the member at a different rate, an intermittently operated eccentric, and connections between said eccentric and one of the grinding members for intermittently imparting an additional movement to said member to break up the continuity of the path of relative movement of the lens holding and grinding members.

In testimony whereof we affix our signatures in presence of two witnesses.

GEORGE H. DAY.
LUCIAN W. BUGBEE.
